Patented Oct. 16, 1917.

Inventor

Anton Ollariu

By his Attorney

Oscar Geier

UNITED STATES PATENT OFFICE.

ANTON OLLARIU, OF PHILADELPHIA, PENNSYLVANIA.

DESIGN FOR A SHOE.

51,388.

Specification for Design.

Patented Oct. 16, 1917.

Application filed June 9, 1917. Serial No. 173,890. Term of patent 3½ years.

To all whom it may concern:

Be it known that I, ANTON OLLARIU, a subject of the King of Hungary, residing at Philadelphia, in the county of Philadelphia and State of Pennsylvania, have invented a new, original, and ornamental Design for a Shoe, of which the following is a specification, reference being had to the accompanying drawing, forming part thereof.

The figure is a perspective view of a shoe showing my new design.

I claim:—

The ornamental design for a shoe as shown.

ANTON OLLARIU.

Witnesses:

JOHN J. GULD,
STEFAN HAJLAMASZ.
